(57) **CLAIM**

The ornamental design for a tripod as shown and described.

DESCRIPTION

FIG. 1 is a front, left and top perspective view of a tripod, showing my new design, with tripod legs in an extended configuration;

FIG. 2 is a rear, right and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1;

FIG. 12 is a perspective view of the tripod with an upper frame unfolded; and,

FIG. 13 is a perspective view of the tripod with the tripod legs in a stowed configuration.

The evenly-spaced broken lines shown in the drawings depict portions of the tripod that form no part of the claimed design. The long dash-short dash broken lines depict areas of enlargement and form no part of the claimed design.

1 Claim, 13 Drawing Sheets
